UNITED STATES PATENT OFFICE.

WILLIAM G. STEIN, OF CANTON, OHIO.

DEFLECTOR AND LIGHT FILTER.

Application filed July 18, 1925. Serial No. 44,558.

The invention relates to means for preventing a glare from automobile headlights, and more particularly to a colored, translucent, perforated shield arranged to be located over the lower portion of a headlight reflector beneath the lamp bulb thereof.

The object of the invention is to provide a segmental deflector and light filter, formed of pyrolin or similar translucent material 10 preferably of a green color, and having perforations therein; a simple and efficient attachment being provided for connecting the deflector to the lamp bulb of the headlight and holding the same over the surface of 15 the reflector, beneath the bulb, whereby all light rays projected downward from the bulb are filtered through the colored deflector, preventing a glare from being directed upward in front of the headlight.

20 An embodiment of the invention is illustrated in the accompanying drawings, in which;

Fig. 1, is a plan view of the improved deflector and light filter.

25 Fig. 2, a sectional view through a headlight equipped with the improved deflector and light filter; and

Fig. 3, a detached view of the attaching clip by means of which the deflector is connected to the lamp bulb.

Similar numerals refer to similar parts throughout the drawings.

The casing of a headlight of conventional form is shown at 1, provided with the usual 35 bowl-shaped reflector 2, upon the inside thereof, the lamp 3, of any usual form, being centrally located within the casing and mounted in the usual socket 4.

The deflector and light filter, to which the 40 invention pertains, may be in the form of a segmental sheet 5, of green pyrolin or similar colored, translucent material having the arcuate, cut away, portion 6, at its apex, a pair of spaced openings 7, preferably reinforced, 45 as by the eyelets shown, being located in the longitudinal axis of the segment, near said cut away portion.

For the purpose of mounting the deflec-

tor within the headlight casing, a spring wire clip 8, formed of a single piece of spring wire, bent upon itself and provided with the central eye 9, and the twisted interengaging fingers 10, as shown in detail in Figure 3, is provided.

The eye portion 9, of this clip, is placed 55 over the neck of the lamp bulb 3, as shown in Figure 2, and the fingers 10, which normally extend in the position shown in Figure 3, are pressed together and inserted through the opening 7, as shown in Figures 60 1 and 2.

The translucent deflector and light filter thus assumes the position shown in Figure 2, covering substantially the lower third of 65 the reflector.

Spaced perforations 11 may be provided in the deflector to permit a small portion of the rays of light from the lamp to pass through the same to the reflector, but it will be seen that as these rays are reflected 70 through the deflector that they will pass through an imperforate portion of the same.

It will thus be obvious that all the rays of light passing downward from the lamp will be filtered through the deflector and light 75 filter, which covers the lower portion of the reflector, thus preventing a glare from being reflected upward above the level of the headlight, all of the uncolored rays of light being reflected from the upper portion of the reflector, downward upon the road in front of 80 the headlight.

I claim:

In combination with a headlight having a bowl shaped reflector and a centrally located lamp bulb therein, a segmental sheet of translucent material covering the lower portion of the reflector and provided with a pair of spaced apertures, and a spring clip having an eye portion surrounding the neck 85 of the lamp bulb and a pair of fingers arranged to be inserted in said apertures.

In testimony that I claim the above, I have hereunto subscribed my name.

WILLIAM G. STEIN.
